ABSTRACT OF THE DISCLOSURE

A configuration of electrical conducting, flexible wires or members arranged to have a height, width, and length. The barrier material being inserted between two conducting surfaces forming portions of an R.F. energy barrier enclosure.

DEDICATORY CLAUSE

The invention described herein may be manufactured, used, and licensed by or for the Government for governmental purposes without the payment to me of any royalty thereon.

BACKGROUND OF THE INVENTION

Shielding devices for covering openings in the past have been in the form of conventional door structures and have not been sufficiently effective since these doors have failed to provide a complete shield for the opening. The reasons for this is that unless one makes the door fit within very close tolerances, a gap or interstice will occur, and electro-magnetic energy may pass therethrough. Further, the joining of any two surfaces, such as connecting flanges in waveguides, has the gap problem. There is, therefore, a need for the present invention which fills these gaps with an R.F. barrier material while at the same time allowing the surfaces to be made at normal or even at large tolerances.

SUMMARY OF THE INVENTION

The R.F. energy barrier material in one embodiment is a wire which is wound, sewn, or formed into an essentially rectangular or coil shape wherein the individual turns of the wire are made to lie side by side. This will give the material height, width, and length dimensions. In another embodiment, rings or cups placed side by side at one or more edges of a core could be used. The barrier material can be used by itself by placing it in a slot or trough which is formed in the door or wall of the enclosure to be shielded. The barrier material can also be wound around, sewn into, or clipped onto a flexible core. The core can be made of insulating or conducting material which may have a greater or lesser resiliency than that of the barrier material. The purpose of the invention is to provide an electrical conducting path between two surfaces of an enclosure used to restrain transmission of radio frequency energy. The two surfaces generally being in imperfect electrical contact and mechanical fit. The barrier material is resilient and arranged so that each turn has essentially an independent action in conforming mechanically to variations in the spacing of the surfaces of the enclosure. Therefore, it permits each of the closely spaced turns to electrically contact the surfaces and complete an electrical circuit. This reduces the space between the surfaces through which the electromagnetic energy can pass.

BRIEF DESCRIPTION OF THE DRAWINGS

FIGURE 1 is a diagrammatic representation of one embodiment of the invention;

2

FIGURE 2 is a diagrammatic showing of the use of the embodiment of FIGURE 1 between two surfaces;

FIGURES 3A-C all show possible end views of embodiments such as that shown in FIGURE 1;

FIGURE 4 shows the use of the invention in a slot contained in one of the two surfaces;

FIGURE 5 is a diagrammatic representation of another embodiment of the invention;

FIGURE 6 is a showing of a possible end view of the embodiment shown in FIGURE 5; and

FIGURE 7 shows the use of the embodiment shown in FIGURE 5 in a slot contained in one of two surfaces.

DESCRIPTION OF THE PREFERRED EMBODIMENTS

FIGURE 1 shows an electrically conductive material 1 in the shape of a wire, such as a copper wire, which is bent into an essentially rectangular shape. The turns are shown far apart in FIGURE 1 so as to show the details. In the actual embodiment all the turns will lie side by side. This will give the wire height, width, and length dimensions. The barrier material 3 being made of a wire or wire-like material will be flexible, and when it is placed between two surfaces 4 and 5, as shown in FIGURE 2, it will make contact with both surfaces all along its length without being a perfect fit.

The wire 1 of the material 3 can be shaped into a rectangular shape, as shown in FIGURE 3A, or it could contain one or two indentations, as shown in FIGURES 3B and 3C. Indentations could also be formed in the other sides of the rectangle as shown in FIGURE 4. These indentations serve to specifically locate the points at which electrical contact is made and/or to modify or relocate the area in which resiliency is experienced. The indentations further provide areas where contact members other than a plane surface may be utilized. FIGURE 4 shows one possible protruding surface, that being a round rod 7 which is attached to or is a part of a door or wall 9. Other protruding shapes such as triangular, trapezoidal, etc. could be used for the rod 7. The other surface 10 has a slot or trough 12 in which barrier material 3 is fitted. For details of how the barrier material may be used in a slot or trough, see U.S. Patent No. 3,296,356 which was issued to applicant on January 3, 1967.

A core 14, seen in FIGURES 3A and 3C, of insulating or conducting material such as rubber or steel wool may be inserted within the opening of the barrier material, or the barrier material could be formed around the core. The core may have a greater or lesser resiliency than that of the barrier material, and it may have other desirable features. The core may fit only within the barrier material (FIGURE 3A), or it may encompass a portion of the turns of the wire (FIGURE 3C). The core can, of course, be made any configuration and have any properties which may be desired by one skilled in the art.

If a core is to be used, then the wire may be sewn or clipped in the core, or the core could be formed about the wire. This is shown in FIGURES 5-7. In FIGURE 5, rings or cups 16 are clipped onto one edge of the core 18. On the other edge of the core is a wire 20 which is sewn in the core. Wire 20 will be in the form of a coil or spiral after it is sewn in the core. The rings and the turns or loops of the wire are shown far apart in FIGURE 5 for clarity; however, in the actual embodiment they will be placed side by side to again form a barrier material having three dimensions. Either one or both edges of the core may have the barrier material. Where both edges are used, the device may be as shown in FIGURE 5, or both edges of the core may have the rings, also both edges may have the coil configuration. In these embodiments, additional resiliency and surface conformance is achieved when a protruding contact member 22 is used as shown in FIG-

URE 7. Additional contact points are also achieved when any of the embodiments are installed in a slot, groove, trough, or device 24 which encloses the barrier material on three sides as shown in FIGURE 7.

In the embodiments of this invention, the conductors are arranged at right angles to the longitudinal axis of the barrier material. By this arrangement, the shortest possible conducting path is presented to any induced electrical current. Because of the numerous closely spaced individually respondent, resilient, springy, electrical contacts, the electrical resistance path between the two conducting surfaces is reduced without a necessity for a high degree of smoothness or alignment of the two surfaces when closed together.

I claim:

1. A system comprising a core means having at least first and second edges, two electrically conductive wire-like means attached to the edges of the core means, said wire-like means being in the configuration of a plurality of rings clipped onto the core means and positioned side by side so as to present height, width, and length dimensions, one of the wire-like means being attached to the first edge of said core means, the other wire-like means being attached to the second edge of said core means, first and second surfaces which are to be placed in electrical contact with each other so as to prevent the passage of electromagnetic energy therebetween, a trough positioned on said first surface and in electrical contact therewith, said wire-like means being positioned in said trough and in electrical contact therewith, a protruding contact member positioned on said second surface and in electrical

contact therewith; and said contact member being in contact with both of said wire-like means along their length dimension.

2. A system as set forth in claim 1, wherein said wire-like means are flexible, and said contact means causes said wire-like means to flex so that the contact means will make contact with each ring of each of the wire-like means.

10 3. A flexible device comprising an electrically conductive wire-like material which is in the configuration of a plurality of turns of identical shape positioned side by side so as to give the device height, width, and length dimensions, each turn being essentially in the form of a rectangle with at least one side containing an indentation, and a flexible core means which is positioned within said turns.
